UNITED STATES PATENT OFFICE.

ASHER LAMBERT, OF NEWARK, NEW JERSEY.

REVERSE-GEAR FOR HOISTING-MACHINES AND ANALOGOUS USES.

No. 913,900.

Specification of Letters Patent.

Patented March 2, 1909.

Application filed December 16, 1907. Serial No. 406,637.

To all whom it may concern:

Be it known that I, ASHER LAMBERT, a citizen of the United States, residing at 1 Johnson avenue, Newark, county of Essex, 5 and State of New Jersey, have invented certain new and useful Improvements in Reverse-Gear for Hoisting-Machines and Analogous Uses, fully described and represented in the following specification and the 10 accompanying drawings, forming a part of the same.

This invention relates to hoisting machines in which, in addition to the drums for the hoisting ropes, it is sometimes necessary to provide a "swinging-drum", to turn a bull-wheel fastened upon a derrick-mast, or for other purposes where a reversible shaft upon the hoister is desired.

In the present invention, the reversing 20 device or mechanism is constructed upon an independent bed-plate and attached to the end of the hoisting machine frame by detachable connections which enable it to be adjusted in the proper position for use with

25 the hoisting mechanism when required, and to be detached and removed at other times. This independent bed-plate is provided with bearings which sustain the parts of the reversing device in an operative condition, and 30 the detachable connections are made adjustable so that the teeth may be carefully adjusted to one another upon cog-wheels journaled respectively upon the main frame and the independent bed-plate. The re-

35 versing device is constructed with a reversible "swinging drum-shaft" and with two "reversing shafts" which are connected by intermeshing gear-wheels so as to revolve in opposite directions and driven by a geared

40 connection with one of the continuously revolving drum-shafts upon the hoister-frame. These reversing shafts are shorter than the drum-shafts so that one end may be journaled in a line with the journals upon the 45 main frame, and the other ends may be supported in bearings upon the independent bed-plate, which can thus be made narrower than the main frame. By bolting an extension bed-piece upon the edge of the inde-

50 pendent bed-plate it can be made of any width desired to correspond with the frames of various hoisting machines, and the same reversing mechanism may therefore be used with hoisting machines of different sizes and

supported by skids secured beneath the 55 frames of such machines. The reversible "swinging drum-shaft" is provided with a cog-wheel and is so mounted in bearings upon the independent bed-plate that the cog-wheel meshes with the two pinions and 60 may therefore be turned in either direction by engaging the suitable pinion with its friction driver.

The invention will be understood by reference to the annexed drawing, in which— 65

Figure 1 is a plan of the reversing device connected to a hoisting machine; Fig. 2 is an elevation of the reversing device and its connection to the frame of the hoisting machine; Fig. 3 is a plan of the hoisting device with the 70 parts upon the reversing shafts in section where hatched; and Fig. 4 is an elevation in section on line 4—4 in Fig. 3. Fig. 5 is a plan, and Fig. 6 an edge view of the bed-plate for the reversing device. 75

The reversing device will first be described, and then its mode of connection with a hoisting machine.

The device has an independent bed-plate *a*, upon which are mounted a pedestal *d'* carrying bearings for the reversing shafts *e*, *e'*, and a pedestal *d* carrying bearings for the said shafts and also for one end of the reversible shaft *c*, and has an extension bed-piece *a'* carrying a bearing for the opposite 80 end of the reversible shaft *c*. The pedestal *d* is also shown with a bearing *f* upon one corner, to carry an intermediate shaft *g* having a gear-wheel *h* for transmitting motion to the shafts *e* and *e'*. The said shafts are connected by intermeshing gear-wheels *i* and *j*, which thus rotate the reversing shafts in opposite directions. The gear-wheels *i* and *j* are provided each with a friction-driver in the form of a cone *k*, and pinions *l* and *l'* are mounted to turn loosely upon the shafts *e* and *e'* and provided each with a friction-seat *m* in the form of a hollow cone fitted to one of the drivers *k*. The reversible swinging drum shaft *c* is shown mounted above the 100 shafts *e* and *e'*, and provided with a cog-wheel *n* which engages the pinions *l* and *l'* and is thus turned in either direction by engaging the suitable pinion with the friction-driver. 105

The means shown for engaging the pinions at will with the drivers is the same as that commonly employed upon the drums of

hoisting machines, and consisting of a cross-key *o* inserted through the reversing shaft adjacent to the outer side of the pinion, and a thrust-pin *p* inserted through the center of the shaft against such cross-key. Thrust-screws *q* and *q'* are mounted in caps or housings *p'* upon the outer bearings of the reversing shafts and are threaded in opposite directions. Cranks *r* upon the outer ends of the screws are connected by a link *s* to turn them simultaneously, and a hand-lever *t* and arm *t'* are connected with the cranks by a link *u*. By forming a connection between the screws to turn them simultaneously, one of them is retracted as the other is advanced, owing to their reverse threading, and the movement of the hand-lever thus operates to press one of the pinions toward its friction-driver and to release the other from its corresponding driver. When the hand-lever stands in its central position as shown in Fig. 4, both the pinions are clear from their drivers, so that although the drivers may be rotated continuously the reversing shaft is not operated until the hand-lever is moved in one direction or the other; which produces a rotation of the shaft in one direction or the other, as desired.

In Fig. 3, swinging drums *v* and *v'* are shown upon opposite ends of the reversible shaft *c* with ropes *V*, *V'* wound thereon in opposite directions, the movement of the drum in either direction thus serving to wind up one of the ropes and pay out the other. To operate such a reversing device with a hoisting machine, skids *w* are projected from beneath the hoister-frame and the reversing-gear-frame (formed of the bed *a* and its pedestals) supported thereon and linked or coupled to the hoister-frame by suitable means, as the tie-bolts *x* shown in Figs. 1 and 2. These bolts are shown provided with jam-nuts *y* and extended into the adjacent sides of the two frames, the nuts serving to lock them firmly in the required position when adjusted. In such power hoisters it is common to mount drums upon the frame intermediate to the ends of the drum-shafts which are supported in suitable bearings, and it is frequently important to project the drum-shafts outside of such bearings at one end and provide each with a winch for hauling in a rope when required.

Fig. 1 shows a means of connecting the reversing device with the hoisting machine, and driving the device from one of the drum-shafts, and at the same time avoiding any interference with the winch upon the overhanging end of the shaft.

In Figs. 1 and 5, *A* represents the frame of the hoisting machine, *B* and *C* drum-shafts mounted in bearings *D* thereon, and *E* gears for driving the said shafts from an engine crank-shaft *F*. *G* and *H* are drums upon the shafts *B* and *C*, the shaft *C* being adjacent to

the end of the frame *A* and having a gear-wheel *I* upon one end outside the bearing *D*, and a winch *J* upon the shaft outside of such gear-wheel. The shaft *B* is also shown with a winch *J'* outside the bearing *D*.

The intermeshing gears *i* and *j* of the reversing shafts are mounted inside the pedestal *d* so that the overhanging drum *v* may set close to the pedestal *d*; but the power to drive the reversing device is most conveniently obtained from the drum-shaft *C* by fitting the gear *I* outside of the bearing, which necessitates the intermediate shaft *g*, and a gear-wheel *I'* upon such shaft.

The engine may rotate the gear-wheels *E* continuously and the drums *G* and *H* be connected therewith by clutches only when desired, and the gear *I* may thus rotate continuously and transmit an uninterrupted motion to the reversing shafts.

The tie-bolts *x* serve first to adjust the gear-wheels *I* and *I'* into suitable mesh with one another, and afterward to hold them firmly in engagement while the reversing device is in use with the hoisting machine. The use of friction-drivers, and the use of screws for pressing the friction-seats upon them in the reversing device, is the same as is common in the type of hoisting machine shown in Fig. 1, where screws *q*² are shown provided with hand-levers *r*² for turning the same independently when it is desired to clutch either of the drums *G* and *H* to its driving-wheel *E*. Such mechanism has been found most efficient and durable in clutching a hoisting drum to its shaft, and is employed in connecting the reversing shafts with the pinions *1* and *1'*, because of its efficiency and durability, and because the operator of an ordinary hoisting machine knows how to use and adjust such a friction device. The screws in the reversing device operate, however, differently from those in the hoisting machine as they are coupled together by the cranks *r* and link *s*, and are reversely threaded, so that the operation of a single hand-lever serves to operate them simultaneously and to slacken one of the screws while tightening the other. This permits the operator, by a single hand-lever, to alternately couple the pinions with their friction-drivers, and to thus impart reversible movements to the shaft *c*.

It is immaterial to the operation of the reversing device itself, as constructed upon its independent frame, how the motion is conveyed to it from the hoisting machine, when connected with a power hoister, and it is obviously immaterial what power is employed to actuate the drums of the power-hoister. Steam engine cylinders *K* and other parts *L* of two engines are shown, as is common where the power-shaft *f* is operated by steam; but electric motors are now employed as commonly as steam for such purpose.

It will be noticed by reference to Fig. 1,

that the reversing gearing does not require so much space as the drums G and H of an ordinary hoisting machine, and that the bed *a* for the reversing device does not require, 5 therefore, to be so wide as the frame A of the hoisting device.

To adapt the reversing device for use with hoisting-frames of various widths, an extension bed-piece *a'*, of suitable width for any 10 particular hoisting machine, is attached to the edge of the bed *a*, as shown in Figs. 1, 5 and 6, by flanges *z* upon the contiguous edges of the beds, and bolts *z'* fitted through the said flanges. In practice, portable hoisting 15 machine frames are made in about three widths, and three different widths of the bed-piece *a'* may therefore be kept in stock for attachment to the edge of the bed *a*, so that the reversing device may be carried in 20 stock and fitted for use with any particular hoister, by bolting a bed-piece *a'* of suitable width to the edge of the bed *a*. It will be noticed that this arrangement leaves a space 25 between the pedestals *b* and *d* in which the connections for the screws *q* and *q'* are located, as shown in Fig. 1, such space being 30 variable according to the width of the frame-piece *a'*, but always permitting the application of the links *s* and *u* inside of the pedestal *b*.

The hand-lever *t* is preferably arranged upon the outside of the pedestal *b*, as shown in Fig. 1, and the arm *t'* upon the inside; a rock-shaft *u'* being attached to both and 35 mounted in bearings in the pedestals *b* and *d'*, to transmit the movement of the hand-lever to the arm and the link *u*.

Having thus set forth the nature of the invention what is claimed herein is:

40 1. In a power hoisting machine, the combination, with the frame A and one or more hoisting drums mounted thereon and a motor with drum-gear-wheels rotated continuously in one direction to turn such drum or drums, of the bed *a* narrower than the hoisting machine frame A, with pedestals *d* upon one side in line with the drum bearings of the main frame and pedestals *d'* upon the other side inside of such line, the extension bed-piece *a'* bolted to the bed-plate *a* making the whole of the same width as the main frame, and having the pedestal *b* upon its outer edge, a reversible swinging-drum-shaft mounted in the pedestals *b* and *d* with the cog-wheel *n* thereon between the pedestals *d* and *d'* and having a swinging drum upon the end, the reversing shafts *e*, *e'*, mounted in the pedestals *d*, *d'*, and having the pinions *l*, *l'* fitted to turn thereon and meshing with the gear-wheel *n*, gear-wheels *i* and *j* connecting the reversing shafts, gearing connecting such wheels with the continuously rotating drum-gear-wheel upon the main frame, and means for alternately connecting the pinions *l*, *l'* 45 with their respective reversing shafts to

rotate the swinging-drum-shaft reversely as desired.

2. In a power hoisting machine, the combination, with the frame A and one or more hoisting drums mounted thereon and a 70 motor with drum-gear-wheels rotated continuously in one direction to turn such drum or drums, of the bed *a* narrower than the hoisting machine frame A with pedestal *d* upon one side in line with the drum-bearings 75 of the main frame and pedestal *d'* upon the other side inside of such line, the extension bed-piece *a'* bolted to the bed-plate *a* making the whole of the same width as the main frame, with the pedestal *b* upon its outer 80 edge, a reversible swinging - drum - shaft *c* mounted in the pedestals *b* and *d* with the cog-wheel *n* thereon between the pedestals *d* and *d'* and having a swinging-drum upon the end, the reversing shafts *e*, *e'* mounted in the 85 pedestals *d*, *d'* and having the pinions *l*, *l'* fitted to turn thereon and meshing with the gear-wheel *n*, gear-wheels *i* and *j* connecting the reversing-shafts, the bearing *f* upon the pedestal *d* carrying the intermediate shaft *g* 90 with gear-wheel *h* upon its inner end connected to the gear *i* upon the reversing shaft, a gear-wheel *I'* upon the outer end of the shaft *g*, and a gear-wheel *I* upon the end of an adjacent continuously rotating drum-shaft, meshing therewith, whereby the shafts *e* and *e'* and the swinging-drum shaft are driven reversibly by the continuously 95 rotating drum-shaft.

3. In a power hoisting machine, the combination, with the frame A and one or more hoisting drums mounted thereon and a motor with drum-gear-wheels rotated continuously in one direction to turn such drum or drums, of the bed *a* narrower than the hoisting machine frame A, with pedestals *d* upon one side in line with the drum bearings of the main frame and pedestal *d'* upon the other side inside of such line, the extension bed-piece *a'* bolted to the bed-plate *a* making the whole of the same width as the main frame, and having the pedestal *b* upon its outer edge, a reversible swinging - drum-shaft *c* mounted in the pedestals *b* and *d* with the cog-wheel *n* thereon between the pedestals *d* and *d'* and having a swinging-drum upon the end, the reversing shafts *e*, *e'* mounted in the pedestals *d*, *d'*, the gear-wheels *i* and *j* connecting the reversing shafts, and gearing connecting them with a 100 continuously rotating drum-shaft upon the main hoister-frame, pinions *l*, *l'* fitted to turn upon the reversing shafts *e* and *e'*, such pinions and the gear-wheels *i* and *j* being provided with friction - seats and friction-drivers, the housings *p* upon the bearings of the reversing shafts upon the pedestal *d'*, with screws *q* and *q'* fitted thereto having the cranks *r* secured adjustably thereon, and connected by link *s*, the pins *p* and cross- 105 110 115 120 125 130

keys *o* in the reversing shafts for operating the friction-clutches, the arm *t'* connected with the cranks by the link *u*, all of such screw-actuating devices lying between the 5 pedestals *b* and *d'*, and a hand-lever *t* for actuating the arm *t'* to engage the pinions *l*, *l'* alternately with their respective shafts.

In testimony whereof I have hereunto set my hand in the presence of two subscribing witnesses.

ASHER LAMBERT.
